(57) **CLAIM**

The ornamental design for a drain pan guard, as shown and described.

DESCRIPTION

FIG. 1 depicts a front perspective view of the drain pan guard;

FIG. 2 depicts a back lower perspective view thereof;

FIG. 3 depicts a top view thereof;

FIG. 4 depicts a back view thereof;

FIG. 5 depicts a first side view thereof;

FIG. 6 depicts a front side view thereof;

FIG. 7 depicts a bottom view thereof; and,

FIG. 8 depicts the drain pan guard in context, disposed in an emergency drain pan.

The broken lines are used to show unclaimed portions of the invention and form no part of the claimed design.

1 Claim, 8 Drawing Sheets
